US00D998592S

(12) **United States Design Patent** (10) **Patent No.:** **US D998,592 S**
Pratley et al. (45) **Date of Patent:** **** Sep. 12, 2023**

(54) **EAR DEFENDER EAR CUP**

- (71) Applicant: **JSP Limited**, Oxford (GB)
- (72) Inventors: **David Pratley**, Oxford (GB); **Tom Malloy**, Oxford (GB)
- (73) Assignee: **JSP Limited**, Oxford (GB)
- (**) Term: **15 Years**
- (21) Appl. No.: **29/856,545**
- (22) Filed: **Oct. 14, 2022**

Related U.S. Application Data

- (62) Division of application No. 29/731,813, filed on Apr. 17, 2020, now Pat. No. Des. 968,365.

(30) **Foreign Application Priority Data**

- Oct. 18, 2019 (EM) 007061114-0004
- (51) **LOC (14) Cl.** **29-02**

Primary Examiner — Paula Allen Greene*(74) Attorney, Agent, or Firm* — Faegre Drinker Biddle & Reath LLP(57) **CLAIM**

The ornamental design for an ear defender ear cup, as shown and described.

DESCRIPTION

FIG. 1 is an isometric perspective view of an ear defender ear cup, illustrating our new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines depict portions of the ear defender ear cup that form no part of the claimed design.
